CONDITIONING FIBERS

Edward Hurst, West Newton, Mass., assignor to
B. F. Perkins & Son, Inc., Holyoke, Mass., a corporation of Massachusetts

Application February 28, 1946, Serial No. 650,920

1 Claim. (Cl. 19—66)

1

This invention relates to improvements in textile fiber conditioning and this application is a continuation in part of an application, Serial No. 647,749, filed February 15, 1946, pertaining to apparatus for and methods of conditioning textile fibers.

The principal objects of the invention are directed to the provision of a novel method of conditioning fibers by removing foreign substances therefrom and treating said fibers with a liquid all to the end that the fibers are free from unwanted foreign matter and in condition for the utmost efficiency and economy in subsequent processing operations.

The invention is adapted for broad application but will be described for purposes of disclosure in connection with wool fiber. Such fiber usually contains considerable foreign matter and requires the application of a liquid usually of an oily nature for subsequent processing thereof.

The invention may be employed at various stages in the processing of the fibers as between the first and second carding operations or otherwise as may be desired.

It is well known that wool fibers contain foreign matter or bodies which must be removed or separated therefrom for the desired results in subsequent processing of the fibers.

Such foreign substances may take many forms such as vegetable particles consisting of burs, seeds, leaves, stalks, small twigs, and pieces of wood, manure, dirt and the like which are usually elongated bodies. The bodies are considerably larger in size than the fibers which are ordinarily in the neighborhood of one thousandth of an inch in diameter and have an inherent tendency to cling to the scales or serrations of the fibers, are usually disposed in opposition to the fibers, and are entangled therewith to large extent.

It has been known to pass a thin web of fiber through the bite of smooth coating pressure rolls in an attempt to remove foreign substances or to facilitate the removal thereof but the results, however, have not been satisfactory for many reasons. More particularly the foreign particles are crushed and flattened out by these rolls so as to tend to adhere more securely to the fibers and make removal difficult if not impossible while the fibers themselves are broken and otherwise injured by the pressure employed.

According to the novel features of the invention, as will hereinafter more fully appear, the fibers and foreign bodies are so relatively disposed that said bodies are readily reduced by comminuting or pulverizing into very small particles without injury to the fibers so as to be removed from the fibers subsequent to which said fibers are treated by or subjected to the action

2

of a liquid. In the practice of the invention, the foreign bodies are acted upon without injury to the fibers. The fibers, for the practice of the invention, will be in some such form as a sliver 5 with the foreign bodies dispersed therein in haphazard fashion and intermingled with the fibers as they ordinarily are in all forms of fiber.

In the drawings the figure is a diagrammatic sectional elevational view through an apparatus 10 adapted for the practice of the invention.

Referring now to the drawings more in detail, the invention will be fully described.

Drawing rolls 2 are arranged in pairs 2, 4 and 6 and the sliver is passed into and through the 15 pairs of rolls successively.

By passing the sliver through the drawing rolls it is progressively flattened and attenuated or drawn out to form a relatively thin web. By the drawing action the fibers are elongated from their 20 natural more or less kinked condition and brought into parallelism which action tends to bring the particles or bodies of foreign matter which are usually elongated into parallelism with the fibers. That is, the foreign substances which are ordinarily elongated bodies are displaced from their haphazard positions into substantial parallelism relative to the fibers for the action of means for comminuting or reducing the foreign bodies.

The web as it leaves the rolls 6 is very thin and 25 practically gossamer-like and is received between an extender 10 consisting of coating rolls 12 which are maintained in yielding engagement for yielding pressure.

These extender rolls 12 in a general way are 30 provided with surfaces formed with axially or longitudinally extending very small coating alternate teeth and grooves arranged and adapted for a rolling and sliding action. As the thin web passes therebetween the teeth act on the foreign bodies in such a way as to divide them into shorter lengths by a tensioning and sliding action. The said teeth are arranged and adapted to act on the foreign bodies with the sliding and rolling action so that said bodies are not only divided but there may be some pulverizing action as well, all without injury to the fibers. This is to be distinguished from the action of coating smooth surfaced pressure rolls which press on the foreign bodies to crush and flatten them as well as press on the fibers to injure them.

From the extender 10 the web, with the subdivisions of the foreign bodies in parallelism with the fibers, is received by and passes between a second extender 14 formed by coating rolls 16 55 which are yieldingly maintained in operative engagement for exerting yielding pressure.

These rolls 16 have surfaces formed with longitudinally spaced circumferentially extending al-

ternate coating teeth and grooves. The thin web of fibers including the shorter lengths of foreign bodies passes between these extender rolls the teeth of which are adapted to act on the foreign bodies with a sliding or splitting action for a lengthwise splitting or separation thereof without injury to the fibers.

By subjecting the fibers to the drawing action so as to align the foreign bodies with the fibers and then subjecting the bodies to the first and second extenders the said bodies are first separated longitudinally into relatively shorter lengths which are split lengthwise. The operations referred to result in a very great reduction in the size of the foreign bodies so that the particles are easily and readily released by the fibers.

From the extender 14 the web of fibers is received on and transported by a foraminous cylinder or screen 18 rotatable in one direction relative to a stationary hollow tube 20 which is provided with a slot 21, then onto a similar screen 22 rotatable in an opposite direction relative to a stationary hollow tube 24 which is also provided with a slot 25. The web is delivered from the screen 22 onto a delivery device which may be a belt 28 propelled by a roll 30.

As the web leaves the screen 22 the web moves past a device 32 for applying moisture thereto. Said device may have as many discharge orifices or discharge ports as may be desired.

The hollow tubes or cylinders 20 and 22 will be connected to a suitable source of suction so that there will be a suction action at the slots thereof and through the screens. The liquid delivery member 32 will be connected to a supply of liquid to be applied to the fibers of the web.

The screens 18 and 22 and the cylinders 20 and 24 will be subjected to a vibrating or a shaking action similar to the vibrations imparted to the wire of a Fourdrinier paper making machine by a shake mechanism or may in some other well known manner be vibrated at relatively high frequency and small amplitude.

The various rolls, screens and rotatable elements will be operatively connected in timed relation for the desired relative speeds so as to obtain the desired drafting of the fibers. There may be drafting between the pair of rolls 6 and the extender 10 and extender 14 should the same be desirable and the web will leave extender 14 at a considerable lineal speed.

As the web of fibers leaves the extender 14 and is received on the screen 18 it is transported circularly in one direction at high lineal speed and being vibrated the foreign particles fall from and are thrown from the web and as the web passes over the slot 21 of cylinder 20 it is subjected at one side to suction to further remove particles. Then as the web is received on and transported by the screen 22 in an opposite direction the vibrating action eliminates particles while as the web passes over slot 25 it is subjected on its opposite side to suction. Thus by transporting the web so that opposite sides are disposed outermost and at the same time vibrating the web in conjunction with subjecting opposite sides of the web to suction the foreign particles are eliminated so that clean fibers are moved past the liquid applying means onto the discharge means. The foreign particles may be received in hoppers 34 and 36 and otherwise are drawn from the cylinders 20 and 24 by suction.

The liquid to be applied to the very thin web may take various forms one common form of which is an oily substance, or an emulsion in-

cluding a suitable oily constituent. The liquid will preferably be atomized or sprayed onto the fibers of the web in a direction agreeing with the direction of movement of the web which is moving at a high rate of speed. It is desired that the fibers or the formation of the web be not disturbed and is accomplished by directing the liquid as described and discharging it so that it strikes the web at a velocity agreeing with that of the web or at a slightly greater speed.

It is desired that the sliver be free from oil prior to the action of the rolls. When oil is applied to fibers containing foreign substances it not only tends to cause foreign substances to adhere to the fibers but applied to such fiber it is not distributed uniformly so as to unfavorably affect yarn sizes, dyeing operations and the like.

When applied after the removal of the foreign particles according to this invention, a minimum of oil will be used and the desired uniform distribution obtained all to the end that the fibers are conditioned economically and efficiently for subsequent processing thereof.

Altogether a novel method of conditioning fibers is provided wherein related steps are performed in sequence and cooperate with one another for the desired results.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claim are therefore intended to be embraced therein.

What it is desired to claim and secure by Letters Patent of the United States is:

A continuous method of removing foreign bodies from a sliver of fibers which consists in, drawing said sliver into the form of a gossamer like web to bring the fibers into substantial parallelism and position the foreign bodies in substantial parallelism therewith, subjecting the web to the action of first means to divide the foreign bodies transversely into shorter lengths, subjecting the web to the action of second means to split the lengths of foreign bodies lengthwise into particles disposed in substantial parallelism with the fibers, and in subjecting said web to centrifugal force, vibrations and suction to remove the particles therefrom.

EDWARD HURST.
